UNITED STATES PATENT OFFICE

2,436,878

INHALER

Joseph B. Biederman, Cincinnati, Ohio

Application March 2, 1945, Serial No. 580,629

6 Claims. (Cl. 128—198)

1

This invention relates to improvements in an inhaler and particularly to the casing or container for medicines.

It is the principal object of this invention to provide an inhaler which does not require an extraneous member for closing same when not in use.

Another object of this invention is the provision of an inhaler which embodies means for varying the opening to the inhaler whereby the flow through the inhaler may be varied as to quantity, thereby varying the amount of medicine-laden air withdrawn from the inhaler.

Another object of the invention is the provision of an inhaler formed in the main of a plastic with which metal parts cooperate to avoid the inherent difficulty of operation of the parts due to the medicine attacking the same when all are made of plastic.

It is also an object of this invention to provide an inhaler which is attractive and pleasing, yet economical to manufacture and produce, whereby the inhaler is economical to purchase.

Other objects and advantages of the present invention should be readily apparent by reference to the following specification considered in conjunction with the accompanying drawings forming a part thereof, and it is to be understood that any modifications may be made in the exact structural details there shown and described, within the scope of the appended claims, without departing from or exceeding the spirit of the invention.

In the drawings:

Fig. 1 is an external, elevational view of an inhaler in its inoperative position.

Fig. 2 is a view similar to Fig. 1 with the parts in position for use.

Fig. 3 is a top plan view of the inhaler as seen in Figs. 1 and 2.

Fig. 4 is a bottom plan view of the inhaler of Figs. 1 and 2.

Fig. 5 is a vertical, sectional view taken on line 5—5 on Fig. 1.

Fig. 6 is a vertical, sectional view taken on line 6—6 on Fig. 2.

Fig. 7 is an enlarged, transverse, sectional view taken on line 7—7 on Fig. 5.

Fig. 8 is an enlarged, transverse, sectional view taken on line 8—8 on Fig. 6.

Fig. 9 is a perspective view of a member operable for opening and closing the inhaler.

Throughout the several views of the drawings similar reference characters are employed to denote the same or similar parts.

2

The inhaler container or casing of this invention comprises a body member 10 preferably, though not necessarily, formed of plastic material having its upper end tapered as at 11, terminating in a comparatively small top 12, which, in use, is adapted to be inserted within the nostril. The lower end of the body 10 is open as at 13, thereby resulting in a body member having its major portion cylindrical in form and hollow. Upwardly of the open end 13 the body member is provided, preferably, at diametrically opposite points with an opening or aperture 14 and 15. Projecting from one of the openings, 15 for example, downwardly to the end thereof, is a slit 16. The top 12 is provided substantially centrally thereof with an opening or aperture 17.

Disposed within the body 10 is a medicine wick carrier and closure member 18 formed of a length of a metal strip transversely arced to relatively closely fit the inner surface of the body member 10. The member 18 is of less height than the body 10, and is provided at its upper end with a top portion 19 from which extend arms 20 and 21. The upper ends of each arm 20 and 21 are inwardly tapered as at 22 and 23 to approximate the taper 11 of the body 10. The lower ends of the arms 20 and 21 are respectively bent normal to their arms inwardly to overlap one another as at 24 and 25. Upwardly of the ends 24 and 25 the arms 20 and 21 are respectively provided with an aperture 26 and 27 which are of an area substantially equal to the openings or apertures 14 and 15 of the body 10, and with which the said apertures 26 and 27 respectively cooperate, as will later be made clear. Secured to, and projecting from one of the arms, 21 for example, at a point below its aperture 27 is a finger piece 28 having a reduced neck portion 29 between itself and the arm. The finger piece 28 may take any suitable or desirable form, such for example as illustrated in Fig. 8, simulating the well-known paper fastener, having legs 30 and 31 which simultaneously pass through a suitable aperture 32 in the arm 21 and are then bent and secured to the inner surface of the arm 21. Projecting from the top 19 of the member 18 is a boss or knob 33 whose function is to close the aperture 17 when the inhaler is not in use.

As noted above, the member 18 is adapted to carry the medicine wick and this is illustrated in phantom lines at 34 in Figs. 5 and 6. The manner of placing the wick in the member 18 may be any desirable one, it being found that the wick having a certain amount of resilience it will of its own accord tightly engage the inner surfaces

of the arms 20 and 21, and thereby be retained in position.

The lower end of the body 10 is closed by a cup-like bottom member which comprises a bottom 35 with a flange 36 extending upwardly from its perimeter. Flange 36 is adapted to receive the lower open end 13 of the body 10.

In order to retain the said bottom member on the body 10, the said body member 10 is provided with apertures 37 and 38, preferably at diametrical points, and receive therein lugs or projections 39 and 40 extending inwardly of the bottom member flange 36.

It is believed that the operation of the inhaler is evident from the foregoing description and the attached drawing. It is, however, as follows:

The member 18 is formed as illustrated in Fig. 9 preferably of non-corrosive metal, aluminum for example. The bottoms 24 and 25 are not secured to one another, wherefore the inherent spring in the metal causes the arms 20 and 21 to tend to spring away from one another. A wick 34 is inserted between the arms 20 and 21 as illustrated in Figs. 5 and 6. The member 18 with its wick is then inserted as a unit within the body 10, placing the neck 29 of the finger piece 18 within the slit 16 of the body 10. The member 18 may then be inserted completely within the body 10. The parts are so arranged that just before or at the time the finger piece 28 reaches the upper portion of the body aperture 15 the boss or knob 33 of the member 18 engages the aperture 17 and acts as a valve for completely closing this aperture. Again the parts are so designed that with the bottom member on the body member and a withdrawal or downward movement of the member 18 to cause the lower ends 24 and 25 thereof to engage said bottom member, the aperture 17 is open and the apertures 14 and 15 of the body member are in complete registry with apertures 26 and 27 of the member 18. From this it will be seen that with the parts as in Fig. 6, an inhalation through the nostril will draw a maximum amount of air into the lower end of the inhaler, and a maximum amount of medicine-laden air out of the inhaler top opening 17. Adjustment of the member 18 at any point between the two extremes of Figs. 5 and 6 correspondingly varies the amount of air that may be drawn into the lower end of the inhaler and through and out of the inhaler.

As was noted above, by forming the member 18 as well as the bottom member of non-corrosive material, there will be no reaction between the medicine in the wick 34 and said metallic parts to cause difficulty in the operation of the parts.

From the foregoing it is believed now evident that there has been provided an inhaler which accomplishes the objects initially set forth.

What is claimed is:

1. In a device of the class described the combination of a body member having an exit opening in its top and an entrance opening near its bottom, said body member being hollow, a combined medicine stick carrier and closure member within the body member comprising a pair of opposed arms and a top conforming to the interior of the body member and reciprocable relative thereto and having portions adapted to cover the exit and entrance openings when at one end of its reciprocation and uncover said openings when at the other end of its reciprocation, and a finger piece projecting from the closure member for actuating the said closure member.

2. In a device of the class described the combination of a cylindrical body member having a

tapered upper end with a top, said top having an exit opening, said body member having an open bottom, entrance openings in said body member near its open end, a slit in said body member from one of said entrance openings to the bottom, a combined medicine stick carrier and closure member within said body member comprising a pair of opposed arms and a top conforming to the interior of the body member and having portions adapted to close the exit and entrance openings, a finger piece carried by the closure member projecting through the slit for operating same to effect the closing of said openings, and a bottom member on the body member for closing its open bottom.

3. In a device of the class described the combination of a cylindrical body member having a tapered upper end with a top, said top having an exit opening, said body member having an open bottom, entrance openings in said body member near its open end, a slit in said body member from one of said entrance openings to the bottom, a combined medicine stick carrier and closure member within said body member comprising a pair of opposed arms and a top formed of material relatively narrow, but wide enough to cover the exit and entrance openings of the body member and transversely formed to conform to the interior of the body member, said closure member being reciprocable from a closing to an opening position, a finger piece carried by the closure member projecting through the slit for reciprocating the closure member, and a bottom member on the body member for closing its open bottom.

4. In a device of the class described the combination of a cylindrical body member having a tapered upper end with a top, said top having an exit opening, said body member having an open bottom, entrance openings in said body member near its open end, a slit in said body member from one of said entrance openings to the bottom, a combined medicine stick carrier and closure member within said body member comprising a pair of opposed arms and a top formed of material relatively narrow, but wide enough to cover the exit and entrance openings of the body member and transversely formed to conform to the interior of the body member, said closure member being reciprocable from a closing to an opening position, a valve like protuberance on the closure member for closing the exit opening when said closure is at one end of its reciprocation and openings in said closure member for registry with the body member entrance openings when the closure member is at its other end of reciprocation, a finger piece carried by the closure member projecting through the slit for effecting the reciprocation of the closure member, and a bottom on the body member for closing its open bottom.

5. A combined medicine stick carrier and closure member formed of a single length of material folded intermediate its ends to provide a top and arms depending from opposite sides of said top with the lower ends of said arms bent toward one another to form a bottom, said arms being transversely curved and provided with apertures, and an operating finger piece projecting from one of said arms.

6. A combined medicine stick carrier and closure member formed of a single length of material folded intermediate its ends to provide a top and arms depending from opposite sides of said top with the lower ends of said arms bent toward one another to form a bottom, said arms being transversely curved and provided with apertures,

a protuberance from the top to act as a closure valve, and an operating finger piece projecting from one of said arms.

JOSEPH B. BIEDERMAN.
